MATCH BOX

Harry Epstein, P.O. Box 27, Willowdale,
Ontario, Canada

Filed Dec. 18, 1967, Ser. No. 9,843

Term of patent 14 years

U.S. Cl. D9—223
Int. Cl. D9—04

The bottom and end of the box not shown in the drawing are identical with the top and end of the box disclosed in FIGURE 1.

I claim:

The ornamental design for a match box, as shown and described.
